UNITED STATES PATENT OFFICE.

JAMES C. DAWSON, OF ST. LOUIS, MISSOURI, ASSIGNOR TO SIEBER & TRUSSELL MNFG. CO.,
A CORPORATION OF MISSOURI.

LOOSE-LEAF BINDER.

No. 888,788.

Specification of Letters Patent. Patented May 26, 1908.

Application filed March 29, 1907. Serial No. 365,215.

To all whom it may concern:

Be it known that I, JAMES C. DAWSON, a citizen of the United States, and resident of St. Louis, Missouri, have invented certain new and useful Improvements in Loose-Leaf Binders, of which the following is a specification, and which are illustrated in the accompanying drawings, forming a part thereof.

The invention relates to loose leaf binders of that type comprising sheet-holding mechanism which includes a plurality of openable filing rings, and which is adapted to be secured within a pair of book covers.

More particularly, the invention relates to loose leaf binders of this type in which each of the filing rings is composed of a pair of pivotally-mounted mating sheet-receiving prongs which are swung on their pivots to open or close the filing rings by a cam slide which is conveniently accessible from the end of the book.

The object of the invention is to simplify and improve the construction and operation of devices of this kind; and the invention contemplates sheet-holding mechanism for a loose leaf binder which is of compact form and which may be successfully employed in connection with book covers of moderate size.

20 In the accompanying drawings Figure 1 is a plan view showing the covers and sheet-holding mechanism of a loose leaf book embodying the invention, the parts of the sheet-holding mechanism being open; Fig. 2 is a 25 sectional view taken on the line 2—2 of Fig. 1, and shows the parts of the sheet-holding mechanism in closed position; Fig. 3 is similar to Fig. 2 but shows the parts in open position; and Fig. 4 is a sectional view taken 30 on the line 4—4 of Fig. 1, showing the parts of the sheet-holding mechanism in closed position.

The book covers or side members of the binder are shown at 10 and 11, and each of 45 these cover members has a flexible connection with a back section 12. Preferably the back section 12 is composed of two-ply material, and embedded between its inner and outer layers 13, 14, is a sheet metal plate 15 which is curved to give to the back of the book the customary rounded form.

At each end of the plate 15 there is provided a lug, as 16, 17, which projects through the inner layer 14 of the back section of the 50 covers and serves for the attachment of the

sheet-holding mechanism. As shown this mechanism comprises a base-plate 18 having upturned marginal edges 19, 20, each of these edges being formed with a marginal bead 21 which provides a longitudinal flange 60 at each side of the base-plate 18 and a channel within the flange. A plurality of openable filing rings are provided for receiving the sheets to be bound, and each of these rings comprises a pair of curved prongs 22, 23, each of which is provided with a pivot 24 which extends transverse to the plane of curvature of the prong.

In assembling the parts the pivots 24 of the prongs 22, 23, are seated within channels 70 provided by the marginal beads 21 of the base plate, the inner ends of the prongs extending over the base plate, as indicated at 25, 26, and the outer ends of the prongs being movable toward and away from each 75 other to close or open the filing rings. The prongs 22, 23, are secured in place by a cover member 27, which is preferably longitudinally slidable on the base plate 18 and is provided with cams for swinging the prongs. 80

As shown the cover member 27 has overturned longitudinal edges 28 and 29 which slidably engage the marginal flanges of the base plate provided by the beads 21, its overturned edges being recessed, as indicated at 30 and 31, to receive the prongs 22, 23, the ends of these recesses engaging the prongs to limit the longitudinal movement of the cover member. One end 32 of the cover member 27 is upturned to provide a 90 thumb-piece for actuating the cover, and cams 33, 34, are provided for engaging the inner ends 25, 26, of the prongs 22, 23, by depressing portions of the cover member along its median line. These cams 33, 34, 95 each have an inclined forward face which bears downwardly on the prongs 22, 23, between their pivots when the cover member 27 is moved to the position shown in Fig. 2 to close the filing rings. 100

To open the filing rings when the cams 33, 34, are withdrawn by the movement of the cover member to the position shown in Fig. 3, springs 35 react upwardly on the inner ends of the prongs 22, 23. As shown each of these 105 springs is secured to the base plate 18 by having its inner end 36 offset and passed through an opening 37 in the floor of the base plate. They cannot, therefore, be removed without first being turned to a 110

substantially vertical position, and this is prevented when the parts are assembled by the engagement of the outer ends of the springs with the prongs 22, 23, of the filing rings.

10 The sheet-holding mechanism of the binder is permanently secured to its covers by clenching over the lugs 16, 17, provided in the back section of the covers, into the ends of the base-plate 18. The prongs 22, 23, of the filing rings are rigidly held by the cams 33, 34, to prevent the removal of sheets from the binder when the parts are in the closed position, and they are quickly and 15 easily moved to a wide open position by pulling outwardly on the thumb-piece 32. The sheet metal parts of the binder may all be formed with a punch and die, and the only tools required for assembling the parts are 20 those necessary for clenching over the lugs 16, 17, and the overturned marginal edges 28, 29, of the cover member 27 to prevent its removal.

I claim as my invention—

25 1. In a loose leaf binder, in combination, a base plate, an openable filing ring comprising a pair of curved prongs each pivotally mounted on the base plate adjacent one edge thereof to swing in the plane of its curvature 30 and each of the prongs extending inwardly beyond its pivot over the plate, a slide carried by the base plate and passing through the filing ring, and a cam carried by the slide and adapted to bear downwardly on both 35 prongs of the ring between the pivots.

2. In a loose leaf binder, in combination, a base-plate of sheet metal having upturned longitudinal marginal edges, each of such edges of the plate being provided with a bead 40 forming a marginal flange for the base plate and a longitudinal channel within the flange, a pivot located within the channel at each side of the base plate, mating sheet receiving 45 prongs carried by the pivots, a slide forming a cover for the base plate, the longitudinal edges of the slide being overturned to engage

with the flanges of the base plate and being recessed to receive the prongs, and prong-actuating cams carried by the slide.

3. In a loose leaf binder, in combination, a 50 base plate of sheet metal U-shaped in transverse section, the upturned edges of the plate being each provided with a bead forming a marginal flange for the base plate and a longitudinal channel within the flange, a pivot 55 located within the channel at each side of the base plate, mating sheet-receiving prongs carried by the pivots, each of the prongs being extended inwardly beyond its pivot over the plate, a slide forming a cover for the base 60 plate, the longitudinal edges of the slide being engaged with the flanges of the base plate and being recessed to receive the prongs, a cam carried by the slide and adapted to bear downwardly on the prongs be- 65 tween the pivots, and a spring reacting upwardly on the prongs between the pivots from the floor of the base plate.

4. In a loose leaf binder, in combination, a 70 base-plate, an openable filing ring comprising a prong pivotally mounted on the base-plate and extended beyond its pivot from the body of the prong over the plate, a slidable plate covering the pivot, the base-plate and slid- 75 able plate having intercalating longitudinal marginal edges, and a cam carried by the slid- 80 able plate for engaging the extended inner end of the prong.

5. In a loose leaf binder, in combination, a 80 base-plate, an openable filing ring comprising a prong pivotally mounted on the base-plate and extended beyond its pivot from the body of the prong over the plate, a slidable plate covering the pivot, the base-plate and slid- 85 able plate having intercalating longitudinal marginal edges, a cam carried by the slid- 85 able plate for engaging the extended inner end of the prong, and a spring opposing the cam.

JAMES C. DAWSON.
